UNITED STATES PATENT OFFICE.

CHARLES S. CRICKMER, OF DALLAS, TEXAS, ASSIGNOR TO THE GUIBERSON CORPORATION, OF DALLAS, TEXAS, A CORPORATION OF DELAWARE.

WELL-DRILLING BIT.

Application filed June 9, 1925. Serial No. 36,025.

This invention relates to new and useful improvements in well drilling bits.

One of the objects of the invention is to provide certain improvements in the structures set forth in co-pending application Ser. No. 749,547 and to add certain other improvements thereover.

An important object of the invention is to mount a plurality of wobbling disks in eccentric relation, whereby in their revolution they will undergo relative radial movement so that drillings lodging between the disks will be displaced radially from the axle thereof, the disks thus being self-cleaning and non-clogging, as well as self-sharpening.

Another object is to provide spacing hubs on the disks which will act to keep the cutting edges of the disks apart and to grind matter lodging between said hubs, due to the shearing action resulting from the eccentric mounting.

A further object is to provide a disk with a flaring bearing aperture which induces wobbling of the disk during revolution and also provides an amplified bearing and wearing surface.

An important object of the invention resides in a novel method of fastening the disk axles or shafts in the bit body, whereby said axles are readily and properly positioned and are held against rotation after being put in place.

Another object of the invention is to provide improved means of mounting and supporting the disks in the bit body and whereby wearing parts may be easily replaced and the main portion of the body preserved.

Another object is to provide an axle provided with eccentric collars but having its bearing ends concentric to the collars contiguous thereto, whereby said axle is balanced and is thus held against rotation.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a front elevation of a bit constructed in accordance with the invention,

Fig. 2 is a side elevation of the same,

Fig. 3 is a vertical sectional view taken on the line 3—3 of Fig. 2,

Fig. 4 is a horizontal cross-sectional view taken on the line 4—4 of Fig. 1,

Fig. 5 is an underside view of the stock with one of the cheek plates in section,

Fig. 6 is an enlarged end elevation of one of the axles,

Fig. 7 is a side view of the bit with one of the cheek plates removed, and

Fig. 8 is a vertical sectional view taken on the line 8—8 of Fig. 5.

In the drawings the numeral 10 designates a bit body or stock having a reduced tapered pin 11 or any other drill stem connection at its upper end. The pin is surrounded by an outwardly directed shoulder 12. The upper portion of the stock is conical although this is merely a preferred design. The stock has its front and rear sides converging downwardly and is formed with a transverse vertical and diametrical socket 13, extending at substantially right angles to said sides. The socket has its side walls converging upwardly to produce a wedge shape.

The upper wedge shaped end 14 of a flat tongue 15 is driven into the socket 13. On each side of the stock are provided flat vertical seats 16 having overhanging shoulders 17. Complementary cheek plates or hangers 18 are formed with flat inner faces 19 for contact with the seats 16. The outer sides or surfaces of the plates are curved to conform to the contour of the stock which at this point is cylindrical as is indicated at 10'. The seats 16 have vertical key-ways 20, which may be dove-tailed or otherwise formed. The plates have vertical keys 21 on their faces 19 shaped to fit in the keyways.

When the key is slid into the key-way from the bottom the shoulder 17 rests upon the top of the plate and said key, thus taking the upward thrust sustained by said plate. The plates have their faces 19 substantially parallel to the sides of the tongue 15 and spaced therefrom. At the lower ends of the keyways the bottom of the stock is formed with sumps 22 (Figs. 3 and 5). By observing Figs. 2, 4, and 5 it will be seen that the front and rear sides of the stock and the edges of the plates are cut at such angles that the lower bearing ends of the plates are in offset relation with respect to a transverse axis passing centrally through the tongue. However

the keys and key-ways are located centrally of the stock and a single locking pin 23 holds the plates against downward displacement; the keys themselves preventing horizontal displacement.

The manner of fastening the pin 23 is unique. At one end the pin has a head 24 countersunk in a counter bore 25 in one of the plates 18 (Fig. 3). This head has a wrench socket 26 (Fig. 2) therein. The other end of the pin is reduced and formed with an inclined annular shoulder 27 (Fig. 5). A shouldered nut 28 is countersunk in a counter bore 29 in the other cheek plate. This has a wrench socket 30 and screws on the end of the pin. The inner end of the nut has an internal bevel 31 which rides upon the inclined shoulder 27 and binds the nut. By removing the nut and withdrawing the pin 23 the cheek plates may be removed. The means of attaching the plates is very satisfactory and tests of the bit in a hole show that the pin does not loosen nor do the plates spread; however any suitable means of fastening the plates may be used.

The plates and tongue support the ends of axles or shafts 32. Each axle is a duplicate of the other and has its outer end engaging in a bearing step 33 in the inner face 19 at the lower end of the adjacent plate 18. At its inner end each axle has a trunnion 34 engaging in a slot 35 in the tongue 15. The axles are placed relatively side by side and each trunnion has a flat side 36 (Figs. 4 and 6). The slot 35 is of such shape and size as to receive the trunnion only when their flat sides are in contact, thus preventing rotation of said axles. However the axles are balanced and counter rotate.

Each axle has formed thereon annular bearing collars 37, 38 and 39 respectively, increasing in diameter and stepped in the order enumerated. The particular construction of the axle is important to the result sought, viz: that of moving the disks radially of each other as they revolve so as to displace drillings lodging therebetween. By observing Figs. 4 and 6 it will be seen that the collars are disposed in eccentric relation and by referring to Figs. 3, 4 and 6, it will be observed that the trunnion 34 of each axle is concentric to the collar 37; while the outer end of the axle is concentric to the collar 39, however this is subject to variation. The collar 38 intermediate the collars 37 and 39 is usually balanced therebetween so as not to influence the axle to rotate. The ends of the axle being concentric to the adjacent collars 37 and 39 preventing rotation of said axle. The flat sides 36 are cut at such points as to position the axles with the greatest projections of their collars in the horizontal plane of said axles and on the front side with relation to the rotation of the bit stock.

On each collar 39 is mounted a circular

cutter disk 43; on the collar 38 a circular cutter disk 42 and on the collar 37 a circular cutter disk 41. The disks increase in diameter outwardly from the center disk 41, thus being stepped at the bottom of the drill. Each disk has a double flared central bearing aperture 40, the least diameter of which is greater than the diameter of the collar on which it is mounted. The intermediate disk 42 of each axle has a concentric hub boss 44 on its side next to the disk 41, which latter has a concentric hub boss 45 contacting with the boss 44. The disk 42 has on its other side a concentric boss 46 larger in diameter than the boss 44 and engaging a boss 47 on the side of the disk 43.

The flared aperture 40 of each disk extends through its boss or bosses and the bearing surface thereof is struck on a continuous curve or convex arc. This plays an important part in the dominating feature of this invention, which is the wobbling of the disks. It is pointed out that each collar has a bearing face or periphery of greater width than the hub of the disk mounted thereon, thus providing for lateral play or movement of each disk independently of the other disks on the same axle and permitting a rocking or oscillating motion, due to the double flared aperture. Each disk, owing to the clearance between the curved walls of the aperture and the collar on which it is mounted, is free to undergo a relative radial motion, which tends to amplify its wobbling.

The character of disk mounting which has been pointed out has numerous advantages, such as that of self-sharpening; ready rolling or revolution, which means proper traction; rapid cutting in shale and rock formations as well as in soft and viscous formations; and self cleaning. These disks do not need grease or oil lubrication as the fluid pumped through the drill stem will keep them clean, cool and free from excessive wear on the axles. The disks used are of comparatively small diameters when contrasted with the disks used on drills of this class. Very satisfactory results have been had with a ten inch drill having its largest disk substantially 7 3/4 inches in diameter.

By reason of the eccentric collars the disks are caused to move radially of each other and have those portions lying outwardly of their hub bosses, spaced apart by said bosses. This provides ample clearance between the sides of the disks at their cutting edges and tends to displace, radially, any drillings, rocks or other obstructions lodging between the disks. By having the greatest projections of the collars in the horizontal plane co-incident with the axis of the axle, said disks will undergo their greatest relative displacement at substantially the points of contact with the walls of the hole being

drilled, so that the cuttings lodging between the disks will be carried away from such points of contact, should they lodge between the disks.

5 It is preferable to form the outer edge of each disk with a bevel 48, inclining away from the center of the bit stock, and an annular bearing face 49, the latter being comparatively narrow and forming the cutting edge, its slight width enhancing the wearing qualities and obviating the chipping tendency of a knife edge, until the disk is worn in. The inclination of the bevel 48 induces the disks in revolving to overcome 10 the centrifugal action due to the rotation of the bit body, and tend to move toward the tongue 15; however the stepped order of the disks crowns the bottom of the hole and thus counteracts the inward movement of 15 the disks. This combined action together with the wobbling and oscillating of the disks results in a grinding of the bevels 48, whereby the disks are self-sharpening.

The wearing parts are the cheek plates 18, 20 tongue 15, axles 32 and disks. By simply taking out the pin 23 all of the parts referred to may be removed and replaced or renewed. The sumps 22 give clearance above the disks 43.

30 A well 50 is bored axially in the pin 11 and stock 10 to a point just above the socket 13. Ducts or courses 51 diverge from the lower portion of the well (Figs. 1, 2, 5 and 8) on each side of said socket. Each duct 35 has a flaring mouth 52 at its lower portion, whereby the diameter of the duct is gradually increased as it approaches its discharge end.

40 The ducts are directed downwardly and outwardly and the under face 53 of the stock for each pair of ducts is cut at substantially right angles to the ducts. By this arrangement the ducts discharge over the disks at points adjacent the advance edges 45 thereof instead of at the axles, thus applying the fluid more effectively and more directly to the points of contact with the substance being bored or drilled and making for better cleaning of the disks. By observing 50 Fig. 2 it will be seen that the fluid is discharged substantially tangentially to the disks over the edges thereof and consequently the edges will be cleaned and cooled.

55 The parallel arrangement of the axles whereby said axles are offset, together with their disks, on opposite sides of the transverse axis of the bit is important as it gives the disks the proper drag and roll necessary to successful boring. The stepping of the 60 disks makes the drill self-centering. The curved bearing surfaces of the apertures 40 have a greater area than a cylindrical bore, thus providing amplified wearing surfaces.

65 As hereinbefore brought out, it is desirable that the bores of the disks be made

larger than the diameters of the axles, so that instead of having merely a turning fit and the play usually present, the clearance or play between the journal of each disk and its axle is such as to initially give the 70 disk a very loose fit, whereby it may wobble or oscillate while revolving and may also have a lateral movement and a vertical movement. However, it is obvious that by providing the convex surface 40 in the bore 75 of the disk and allowing the said bore only a turning fit on the axle, the disk would necessarily rock transversely if it was given any clearance at all on each side. Such a mounting would cause the disk to wobble or oscillate and it could also move laterally, however, it would not have any vertical movement. If the convex bores were not used then the bore would have to be large enough to give clearance in excess of that 80 present in the usual turning fit.

Various changes in the size and shape of the different parts, as well as modifications and alterations, may be made within the scope of the appended claims.

What I claim, is:

1. In a multiple cutter disk bit, a bit stock, a pair of axles oppositely directed and mounted in the bit stock on opposite sides of the transverse axis of said stock, and a plurality of disks on each axle disposed in eccentric relation to each other and initially mounted upon said axles with sufficient play to permit lateral movement thereon during revolution.

2. In a multiple cutter disk bit, a bit stock, a pair of axles oppositely directed and mounted in the bit stock, on opposite sides of the transverse axis of said stock, and a plurality of disks on each axle disposed in eccentric relation to each other and initially mounted upon said axles with sufficient play to wobble thereon during revolution.

3. In a multiple cutter disk bit, a stock, two groups of cutters each disposed on opposite sides of the stock, the cutters of a group being mounted in eccentric relation to each other, each cutter being initially mounted with sufficient play at its journal to wobble at its periphery while revolving.

4. In a multiple cutter disk bit, a bit stock, a pair of oppositely directed axles mounted and permanently maintained transversely of the bit stock, and a plurality of cutter disks mounted on each axle each having a spacing boss at its hub and initially mounted on its axle to freely move laterally thereon while revolving.

5. In a multiple cutter disk bit, a bit stock, groups of cutter disks, each group being disposed on opposite sides of the stock, the disks of a group being disposed in eccentric relation to each other, each cutter disk being initially mounted and having sufficient play to move laterally during revolution.

6. In a multiple cutter disk bit, a stock, two groups of cutters each disposed on opposite sides of the stock, the cutters of a group being mounted in eccentric relation to each other, each cutter being initially mounted with sufficient play at its journal to wobble at its periphery while revolving, the outermost disks projecting below the innermost disks.
- 13 7. In a multiple cutter disk bit, a bit stock, a pair of oppositely directed axles having their inner ends supported at the center of the stock, outer members carried by the stock and supporting the outer ends of the axles, and a plurality of cutter disks mounted on each axle in eccentric relation to each other, each disk being initially mounted to shift transversely at its periphery relatively of its cutting arc, while revolving.
- 15 8. In a multiple cutter disk bit, a bit stock, a pair of oppositely directed axles having their inner ends supported at the center of the stock, outer members carried by the stock and supporting the outer ends 20 of the axles, a plurality of cutter disks mounted on each axle in eccentric relation to each other, each disk being initially mounted to shift transversely at its periphery relatively of its cutting arc, while revolving, and ducts for supplying a liquid to the peripheries and sides of the disks.
- 25 9. As an article of manufacture, a circular disk having a cutting edge and provided with a central bore having its walls curved longitudinally thereof.
- 30 10. In a multiple cutter disk bit, a stock having a drill connection at its upper end, supports depending from the lower end of the stock, the outer supports being removable, axles carried by the supports, and a plurality of cutter disks mounted on each axle in eccentric relation between its supports, said disks having a hub-thickness less than the spaces between the supports, whereby said disks are free to move laterally on said axles.
- 45 11. In a multiple cutter disk bit, a bit stock having diametrically opposite seats, cheek plates engaging the seats and depending from the stock, means for fastening the plates on the seats of the stock, a central support depending from the stock between the plates, axles having their outer ends carried by the plates and their inner ends engaged in said central support, and a plurality of cutter disks mounted in eccentric relation on each axle and movable laterally and vertically thereof.
- 55 12. In a multiple cutter disk bit, a bit stock having opposite seats, a removable tongue mounted in the bottom of the stock, cheek plates fitting on the seats and depending from the stock on each side of the tongue, axles having their outer ends supported by the cheek plates and their inner ends en-
- gaged in the tongue on opposite sides of the transverse axis of said bit, means for removably fastening the plates to the stock, and a plurality of cutter disks disposed in eccentric relation and so loosely mounted as to shift laterally on the axles between the tongue and the plates to sharpen and cut while revolving.
13. In a multiple cutter disk bit, a bit stock, supports depending from the stock, transverse axles having their ends carried by said supports and provided with eccentric bearing collars, and cutter disks so loosely mounted on said collars as to shift laterally on said collars and to move vertically thereof to sharpen and cut while revolving.
- 15 14. In a multiple cutter disk bit, a bit stock, supports depending from the stock and spaced apart, transverse axles having their ends carried by the supports, eccentric bearing collars on the axles, and cutter disks having flaring bearing apertures receiving said collars, whereby the disks are mounted to rock on the axles.
- 85 15. In a multiple cutter disk bit, a bit stock, a removable tongue depending from the center of the stock, removable cheek plates secured to the stock on opposite sides of the tongue, transverse axles having their outer ends mounted in the plates, the tongue having a slot for receiving the inner ends of said axles, said axles being held against rotation, eccentric bearing collars carried by the axles, and cutter disks mounted on the collars sufficiently loose to undergo lateral movement therein.
- 95 16. In a multiple cutter disk bit, a bit stock, supports depending from said stock and spaced apart, axles carried by said supports, eccentric collars carried by said axles, and circular cutter disks mounted on the collars and having spacing bosses at their hubs, said disks being movable laterally and radially.
- 105 17. In a multiple cutter disk bit, a bit stock, supports depending from said stock and spaced apart, axles carried by said supports, eccentric collars carried by said axles, and circular cutter disks mounted on the collars and having spacing bosses at their hubs, said disks having flaring bearing apertures surrounding said eccentric collars, whereby said disks are free to oscillate.
- 110 18. In a multiple cutter disk bit, a bit stock having seats on opposite sides and key-ways in said seats, cheek plates engaging said seats and having keys engaging in said key-ways, a fastening pin passing transversely through the stock and plates, axles carried by the plates, a central support carried by the stock, axles carried by the plates and support, eccentric collars on the axles, and laterally movable cutter disks of stepped diameters mounted on said eccentric collars.
- 115 19. In a multiple cutter disk bit, a bit

5 stock having seats on opposite sides and key-ways in said seats, cheek plates engaging said seats and having keys engaging in said key-ways, a fastening pin passing trans-
versely through the stock plates, axles carried by the plates, a central tongue inserted in the bottom of the stock and fastened by the pin, axles carried by the plates and tongue and immovably held in the tongue,
10 eccentric collars on the axles between the tongue and the plates, and cutter disks con-
centrically mounted on the collars and hav-
ing flaring bearing apertures surrounding
15 said collars, whereby said disks are free to
oscillate.

20 20. In a multiple cutter disk bit, a bit stock, supports depending from the lower end of the stock, axles stationary in the sup-
ports and having bearing faces in stepped horizontal planes, and disks mounted on the stepped bearing faces and extending downward to different extents, said disks being sufficiently loose on said bearing faces to move laterally and vertically thereon while
25 revolving.

21. In a multiple cutter disk bit, a bit stock, supports depending from and remov-

ably attached to opposite sides of the stock, a central tongue removably inserted in the stock between said supports and depending 30 from said stock, a fastening device passing through the stock and engaging the supports and tongue in common, axles carried by the supports and tongue, and disks mounted on the axles between the supports and the 33 tongue.

22. In a multiple cutter disk bit, a bit stock, supports at the lower end of the stock, and a plurality of revoluble disks journaled between said supports and having flared 40 bearing supports and sufficient clearance therebetween to rock on said bearings while revolving.

23. In a multiple cutter disk bit, a bit stock, supports at the lower end of the stock, 45 and a plurality of revoluble disks journaled between said supports and having flared bearing supports and sufficient clearance therebetween to rock on said bearings while revolving, the journals of the disks being 50 larger than their supports to permit the disks to move vertically.

In testimony whereof I affix my signature.
CHARLES S. CRICKMER.
